(57) CLAIM

The ornamental design for a TV receiver with pictorial image, as shown and described.

DESCRIPTION

FIG. 1 is a perspective view of the images of the ornamental design of the present invention as shown on a monitor screen;

FIG. 2 is a front elevational view of the ornamental design of the present invention shown in FIG. 1; and,

FIG. 3 is an enlarged view of the TV receiver screen displaying a pictorial image, shown separately for completeness of illustration.

The broken line showing of the TV receiver is included for the purpose of illustrating portions of the article and forms no part of the claimed design.
